APPARATUS FOR DISPENSING FLUIDS FROM
A CONTAINER UNDER PRESSURECharles Whittaker Roberts, Wanstead, London,
England, assignor to Sparklets Limited, Lon-
don, England, a British companyApplication February 15, 1949, Serial No. 76,567
In Great Britain February 4, 1948

2 Claims. (Cl. 222—394)

1

This invention relates to apparatus for dispensing fluent material from a container under pressure. The fluent material may be aerated beverages, liquid medicaments, dentifrices, and insecticides, or more viscous fluids such as aerated cream. This invention relates more particularly to apparatus of the type in which the dispensing of the fluent material is effected by opening a spring-controlled valve mechanism.

In apparatus for dispensing fluent material from a container under pressure as proposed hitherto, difficulty has been experienced in preventing the accretion of the fluent material around the component parts of the valve mechanism, especially around the spring and valve seating and in so constructing and arranging the valve mechanism as to permit of readily dismantling and cleaning of the internal passage.

It is an object of this invention to provide an apparatus of improved construction wherein access of the fluid to the controlling spring is prevented.

Another object is to provide an apparatus, the component parts of which can be easily and rapidly assembled and dismantled.

A further object is to provide an apparatus, the internal passages of which are readily accessible for thorough cleaning.

According to the present invention apparatus for dispensing fluent material from a container under pressure comprises a syphon head adapted to be secured to the container and to a delivery tube extending inside the container near to the bottom thereof, the syphon head having an inlet passage communicating with the delivery tube, an outlet passage for the discharge of fluent material from the head and valve means located between the inlet and outlet passages and operable externally of the head to control the flow of fluent material from the inlet to the outlet passage, the valve means comprising a valve seating, a valve plug and a spring urging the plug on to the seating wherein the spring is housed in a chamber sealed against access of the fluent material to be dispensed and the valve seating is removably mounted in the syphon head.

For attachment to the container, the syphon head may be formed with a threaded portion adapted to engage a corresponding threaded portion of the container. This may be formed by a thread cut on the body of the container itself, or in any other suitable manner, for example by brazing or otherwise fastening a threaded ring on the container.

The invention will now be more particularly de-

2

scribed with reference to the accompanying drawing which shows a side view partly in section of an apparatus for dispensing fluent material from a container under pressure according to the invention.

The syphon head 10 is formed with an annular projection 11, the inner surface of which is adapted threadedly to engage a metal collar 12 mounted on the neck of the container 13, leakage of the pressure fluid between the projection 11 and the collar 12 being prevented by a gasket 14 mounted between the mouth of the container 13 and a shoulder 15 formed on the head 10.

The head 10 is provided with a bore 16 and an exit passage 17 communicating therewith. The lower end of the bore 16 is screw-threaded to receive a threaded plug 18 having an inlet passage 19 concentric with the bore 16. In the lower end of the inlet passage 19 is mounted a delivery tube 20, extending to a point near to the bottom of the container 13. Communication between the inlet passage 19 and the outlet passage 17 is controlled by a valve means comprising a valve plug 21 co-operating with a valve seating 22 mounted on or formed integrally with the plug 18.

The valve plug 21 is mounted on a piston 23, adapted to slide within the upper portion of the bore 16 above the point at which the outlet passage 17 communicates therewith, so as to isolate a chamber 24 at the upper end of the bore 16. This chamber 24 is sealed against access of the fluid under pressure by means of a sealing ring 25 located in a circumferential recess 26 in the piston 23. The sealing ring 25 is preferably made of yielding material and is compressed between the piston 23 and the wall of the chamber 24 whereby access of fluent material to the chamber 24 is prevented. The valve plug 21 is normally held against the valve seat 22 by the action of a compression spring 27 housed within the chamber 24 and protected against access of the fluid by the sealing ring 25, and bearing at one end against the piston 23 and at the other end against a lip 28 formed within the chamber 24.

The piston 23 is coupled to an actuating lever 29 on the outside of the head 10 by means of a stem 30 which is mounted on the piston 23 in axial continuity with the inlet passage 19 and passes through an orifice 31 formed in the upper end of chamber 24. The upper end of stem 30, which is screw-threaded, passes through an orifice 32 in the lever 29 and is secured thereto by a nut 33.

The lever 29 is arranged to pivot about a fulcrum in the form of a boss 34 formed integrally

with the underside of the lever 28 and abutting against the outer surface of the head 10, so that manual depression of the end of the lever 28 remote from the stem 30 raises the stem 30 and the piston 23 against the action of the spring 27 and thus lifts the valve plug 21 from the seating 16. On release of the lever 28, the spring 27 forces the valve plug 21 on to its seating and returns the lever 28 to its original position.

When it is desired to clean the interior of the head 10, the plug 18 carrying the valve seating is unscrewed, and the lever 28 detached from the stem 30, when the piston 23, stem 30 and spring 27 can readily be removed from the head 10 clearing the bore 16 and leaving the chamber 24 housing the piston 23 ready of access for cleaning.

For convenience in handling and operating the apparatus, gripping means in the form of a handle 35 may be attached to the head or formed integrally with it.

In order that the syphon may be charged with gas from a compressed gas capsule, a socket 36 is provided on the container for the reception of a capsule holder during the charging operation.

The head 10 may be formed from metal for example by die-casting or it may be moulded from a suitable synthetic plastic material. The outlet passage 11, or spout as it is commonly termed, may be lined with a tube of corrosion resistant material such as stainless steel, glass or ceramic ware, which may be positioned in the die or mold so that the material of the head is bonded to it during the casting or moulding operation.

I claim:

1. Apparatus for dispensing fluids from a container under pressure comprising a syphon head adapted to be secured to a container, said head having an axial bore therethrough from top to bottom and internally threaded at its lower end, a detachable closure plug threaded in said lower end and having an inlet passage open to said bore, a delivery tube attached to said plug in communication with its inlet passage, said head also having an outlet passage in open communication with the bore, said plug having thereon a

5 valve seat extending into the lower end of the bore, a valve plug reciprocable in the bore in co-operation with said valve seat to open and close the inlet passage from said closure plug, sealing means on the valve plug preventing the passage of fluid to the upper portion of said bore, spring means in the upper portion of said bore urging the valve plug closed against its seat, a valve stem attached at its lower end to the valve plug and projecting at its upper end through the upper end of said bore above the top of the head, an operating handle mounted externally on the top of said head in detachable connection with the projecting end of the valve stem, and all said valve plug, 10 stem, and spring means being bodily removable through the lower end of said bore following detachment of the operating handle and removal of the closure plug.

2. In the structure of claim 1, said operating handle and its detachable connection with the valve stem comprising a lever fulcrumed on the top of the syphon head and having a handle portion and a valve stem connecting portion, said valve stem connecting portion being apertured 15 to receive the upper end of the valve stem therethrough, and detachable securing means on said upper end of the valve stem engaging the stem connecting portion of the lever for moving the stem to unseat the valve plug on actuation of the handle portion of said lever.
